CONNECTING MEANS FOR SHIELDED
IGNITION LEADS

John W. Anderson, Elizabeth, N. J., assignor, by
mesne assignments, to Titeflex, Inc., Newark,
N. J., a corporation of Delaware

Application November 1, 1943, Serial No. 508,634

2 Claims. (Cl. 174—35)

1

This invention relates to the terminal arrangements and connections of a detachable radio shielded spark plug lead and the manifold and manifold conductor, of a radio shielded ignition harness for an internal combustion engine. It may, however, have other applications.

In radio shielded ignition harness of the well-known conventional type there is a manifold which conforms to the shape of the engine, being straight where the cylinders are arranged in straight rows and arc-shaped to embrace the engine shaft when the engine has its cylinders arranged radially as is usually the case in aeroplanes. The manifold is usually rigid and from it extend flexible spark plug leads to the various spark plugs respectively. A conduit also extends from the manifold to the distributor at the magneto, the manifold, spark plug lead conduits and manifold conduit being of metal and grounded. Ignition conductors or cables extend from the distributor through the magneto conduit and into the manifold and thence the individual conductors are connected through the individual spark plug lead conduits with the respective spark plugs.

Where the spark plug lead is detachably connected with the manifold, the manifold conductor extends into the conduit outside the manifold and leading to the spark plug, where it is provided with a terminal at its end which engages the terminal at the end of a conductor leading to the spark plug through the conduit of the spark plug lead. In prior constructions the radio shield about the terminals has been a rigid metal sleeve and the integral insulation along the connected conductors and about the terminals is of considerable length in order to avoid flash-over from the terminals to the metal sleeve. The rigid metal sleeve which encloses such terminals and insulation is, therefore, of considerable length, and renders a considerable portion of the lead to the spark plug inflexible thereby depriving the flexible lead of much of the advantages of adjustability and adaptability which would be realized were the lead flexible at this portion. Especially is this true where the distance between the manifold and a spark plug is small so that the spark plug lead is relatively short and the rigid portion referred to constitutes a greater proportion of the length of the lead.

It is an important object of this invention to make flexible that portion of the lead to the spark plug above referred to as inflexible, so that such lead has the advantages of being flexible substantially from the manifold outlet outwardly. This is accomplished by providing a

2

flexible, metal, radio shielding conduit in place of the above referred to rigid sleeve, making its contained parts capable of flexing so that such lead portion may be flexed and combining such portion with the remainder of the spark plug lead and the manifold outlet.

A further object of the invention is to provide a greater distance of possible flash-over between the terminals referred to and ground for a given axial length of the conduit.

A further object of the invention is to economize material, lessen the weight and lower the cost of the lead by making the flexible portion of the lead other than that containing the engaging terminals and appurtenant insulation, of less diameter than the flexible portion last mentioned whereby all the parts at the different points are accommodated without excessive use of material and the flexibility of the lead as a whole is enhanced.

A further object of the invention is to dispense with the usual metal spring contact at the terminals by providing resilient terminal supporting insulation, pressing the terminals together in assembling and securing them in that relation whereby the insulation will be in a compressed condition and its resilience will yieldingly press the terminals together.

A further object of the invention is to facilitate the assembling of the spark plug lead with the manifold.

Other and ancillary objects of the invention will appear hereinafter.

In the accompanying drawings which illustrate the invention—

Fig. 1 is an elevation, partly in section and partly broken away, of a spark plug lead and a fragment of a manifold showing the connecting and terminal arrangement of a radio-shielded, detachable spark plug lead with the manifold and manifold conductor of a radio-shielded ignition harness for an internal combustion engine, which embody the invention, the parts being shown in assembled condition; and

Fig. 2 is a similar view of the apparatus as shown in Fig. 1, but with the spark plug lead disassembled from the manifold and manifold conductor and with part of the spark plug lead, as shown in Fig. 1, omitted.

Referring to the drawings, there is shown therein but a single spark plug lead and the ignition cable therefor, with sufficient of a manifold to show the application of the invention, although it will be understood that the manifold will, in practice, have sufficient cables and that there

will be a spark plug lead branching therefrom for each spark plug served. The connections, however, of each spark plug lead with the manifold may be as shown in the drawings.

The manifold comprises the metal arc-shaped, tubular portion 1 having an opening 2 and includes the metal nipple or outlet 3 about the opening, secured to the tubular portion 1, such outlet having screw-threads 4 at its outer end and also the inwardly extending flange 5. A cable 6 within the manifold is bent to pass outwardly through the opening 2 and outlet 3 and projects outwardly from the manifold. The cable comprises the flexible, stranded conductor 7 with the usual insulation 8 which leads back through 15 the manifold and the magneto conduit (not shown) to the distributor at the magneto (not shown).

About the cable 6 is a bushing of resilient, flexible insulating material such as rubber, a rubber compound, for instance, such as used by cable manufacturers in insulating flexible electric cable, or a suitable synthetic rubber compound such as neoprene. Such bushing comprises the elbow 9 reenforcing and locating the cable at its 20 end, the flange 10 resting upon the flange 5 of the manifold outlet, whereby the bushing and its enclosed cable are supported, and the tapered body 11 having the electric contact terminal 12 at its end connected to the cable conductor and 25 overlapping the end of the body 11. The bushing may be molded on the cable or be pre-molded and the cable inserted therein.

The spark plug lead comprises a flexible, metal conduit 12' which may be a metal, strip-formed, corrugated tube as shown in the Patent No. 1,198,392 to Louis H. Brinkman (see Fig. 7) covered with a braid of metal strips as shown in Fig. 5 of Patent No. 1,340,818 to said Brinkman. This conduit, at its spark plug end, is soldered to a metal elbow 13 provided with a nut for securing the elbow to the metal shield of a spark plug (not shown), a projection 14 extending within the shield of the spark plug and having a spring 15 establishing contact with the central spark plug electrode. The spring 15 is connected with the conductor of a flexible cable 16 including the stranded, flexible conductor 20 covered with insulation 21 and passing through the elbow and conduit 12'. This construction and connection of 30 the spark plug end of a lead is well known.

At the other end of the conduit 12' from the elbow, the conduit is soldered to a double ferrule 22, there being also soldered to this ferrule, the end of a flexible metal conduit 17 which is also 35 a corrugated tube formed from a metal strip and with a braided covering of metal strips like the tube of the conduit 12', but the conduit 17 is of greater diameter than the conduit 12' to afford 40 space for the separable connections for the cables 9 and 16 and their appurtenant parts.

Within the conduit 17 and substantially filling the same except for the tapered recess about to be referred to, is molded a body 18 of resilient, insulating material, which may be rubber, a rubber compound, as for instance such as employed in insulating, flexible, electric cables, or a suitable synthetic rubber compound such as neoprene. The bushing 18 has a tapered recess 19 in which the tapered body 11 is adapted to fit. The cable 16 enters into the conduit 17, passes through the insulation 18 and has its conductor connected with the electric contact terminal 23 in the bottom of the recess 19.

At the opposite end of the conduit 17 from the

ferrule 22, a ferrule 24 surrounds the conduit. The ferrule 24 has an inwardly and outwardly extending flange 25, the inwardly extending portion substantially covering the end of the conduit including the corrugated tube and its braided covering, while the outwardly extending portion is engaged by the flange of a nut 26 swiveling on the ferrule. The conduit 17, including both the corrugated tube and the braided covering, is securely soldered to the ferrule 24.

The conduit 12' may have molded in it an insulating compound filling the conduit about the conductor 16. Such filling may be the same material as that of the body 18 and is shown as being molded integral therewith.

In assembling the spark plug lead with the manifold, the body 11 is entered within the recess 19, the nut 26 is engaged with the threads 4 on the manifold outlet and when screwed down thereon clamps the ferrule flange 25 against the end of the conduit and the flange 10 of the bushing about the manifold conductor against the outlet flange 5. The parts are thus securely clamped in position with the spark plug lead firmly and securely attached to the manifold. The tapered body of insulation 11 is made of such length and the parts are so proportioned and arranged that when the conduit 17 is clamped in position by the screwing down of the nut 26, the terminals 12 and 23 are pressed together and their supporting resilient material is compressed and exerts a spring pressure holding the terminals in contact at all times so that a metal spring electrode for this purpose is unnecessary. Also it will be observed that the tapered engaging surfaces of the insulation bodies 11 and 18 provide greater security against flash-over from the conductor terminals to ground at the joint between the end of the body 18 and the flange 10 by increasing the distance from such terminals to such joint. The tapering of the body 11 of the bushing about the manifold conductor and of its corresponding recess in the body 18 of the spark plug lead facilitates the entry of the body 11 into the recess 19 in assembling the apparatus and holds the parts more firmly and securely together after assembly.

The conduit being flexible and its contained parts permitting flexing, it will be seen that the flexible length of the spark plug lead is greatly increased in comparison with the previous practice of having a rigid casing about the terminals of the manifold and spark plug lead conductors, and their appurtenant insulation. This increase in flexible length of the spark plug lead is of great practical value in increasing the adjustability and adaptability of the spark plug lead in assembling the harness upon the engine.

While the invention has been illustrated in what is considered its best application it may have other embodiments without departing from its spirit and is not, therefore, limited to the structure shown in the drawing.

What I claim is:

1. The combination with the manifold of a radio shielded ignition harness for an internal combustion engine, said manifold having an opening, of a conductor in said manifold and projecting outwardly from said manifold through said opening, a second conductor for connecting with a spark plug, a flexible metal radio shielding conduit into which said conductors enter, and means for securing said conduit to said manifold, a tapered body of flexible insulation within said conduit supported on the manifold and surrounding

the conductor projecting from the manifold, the last mentioned conductor being supported by said insulation, a terminal at the end of said tapered body of insulation and connected with the first mentioned conductor, a second body of flexible insulation within the said conduit and through which said second conductor passes, said second body of insulation having a tapered recess within which the said tapered body of insulation extends and a second terminal connected to said second conductor at the bottom of said recess and engaging the first mentioned terminal.

2. The combination with the manifold of a radio shielded ignition harness for an internal combustion engine, said manifold having an opening, of a conductor in said manifold and projecting outwardly from said manifold through said opening, a second conductor for connecting with a spark plug, a flexible metal radio shielding conduit into which said conductors enter, means for securing said conduit to said manifold, a body of flexible insulation within said conduit, supported on the manifold and surrounding the conductor projecting from the manifold, the last mentioned conductor being supported by said insulation, a terminal at the end of said body of

insulation and connected with the first mentioned conductor, a second body of flexible insulation within the said conduit and through which said conductor passes, said second body of insulation having a tapered recess within which the first mentioned body of insulation extends and a second terminal connected to said second conductor at the bottom of said recess and engaging the first mentioned terminal.
